Specification for Design.

Patented Jan. 3, 1922.

Application filed August 2, 1921. Serial No. 489,401. Term of patent 3½ years.

To all whom it may concern:

Be it known that I, WILLIAM GORDON HUNTON, a subject of the King of England, residing at London, N. W. 8, England, have invented a new, original, and ornamental Design for a Textile Fabric or Article of Similar Nature, of which the following is a specification, reference being had to the accompanying drawing, forming part thereof.

The figure is a plan view of a portion of a printed fabric showing an embodiment of

my new design. It is to be understood, however, that my new design may be applied not only to fabrics, but also to wall paper, wrapping paper, or similar articles having surface ornamentation, without departing from what I claim as my invention.

I claim--

The ornamental design for a textile fabric or article of similar nature, substantially as shown and described.

WILLIAM GORDON HUNTON.
